VALVED PISTON WELL PUMP

Homer B. Fuqua and Roy H. Covert,
Tucumcari, N. Mex.

Application May 10, 1949, Serial No. 92,466

5 Claims. (Cl. 103—179)

1

This invention relates to fluid distributing apparatus and more particularly to that used as a well cylinder including structure for the pumping of water.

In devices of this general type heretofore in use the pump has usually been constructed to operate on the suction principle although some have operated on the principle of the present invention which involves positioning a portion of the well cylinder below the water level and raising segments of the fluid body by means of a valved plunger. In reciprocating pumps of this type in which a plunger or the like moves within a surrounding casing a leather cup or diaphragm has usually been provided to insure a seal between the edges of the plunger and the casing in order to maintain the suction and prevent the leakage of the water being raised back to a lower level. While this has generally operated satisfactorily the leather or similar material oftentimes has become imbedded with grit or sand which has reduced its efficiency as a seal and produced additional wear on the surfaces which it contacted such as the cylinder or casing wall. This has made the frequent replacement of the cup leathers necessary with the attendant expense and loss of use of the device, in addition to that of the replacement of worn parts.

Accordingly, it is an object of the present invention to provide a well casing construction for pumping water in which the disadvantages set forth above are overcome.

A further object of the invention is the provision of a well casing construction for pumping water in which means is provided for maintaining a seal between the plunger and cylinder which does not necessitate the use of cup leathers and the like.

A further object of the invention is the provision of a well cylinder pump construction which is relatively simple and inexpensive to manufacture, durable, and which is not subjected to unreasonable wear during ordinary usage as a result of foreign matter adhering to any of the movable parts.

Further objects and advantages of the invention will be apparent from the following description taken in conjunction with the accompanying drawings, wherein:

Fig. 1 is a vertical section through a device constructed in accordance with the present invention;

Fig. 2, a section on the line 2—2 of Fig. 1; and,

Fig. 3, a section on the line 3—3 of Fig. 1.

Referring to the drawings, a well casing or

2

cylinder 10 is provided having a lower threaded end 11 to which a cap or retainer 12 is attached, the cap having a flange or lip 13 providing a stop for a plunger, later to be described. The upper end of the cylinder 14 is threaded to receive a well pipe coupling 15 to which additional well sections may be attached or the well housing.

The well cylinder is provided with a plurality of circumferentially spaced ports or apertures 16 which are normally positioned in the well below the water level in order that the water may enter the casing.

A plunger or pump member 17 of substantially cylindrical form is positioned within the well cylinder, the clearance between the plunger and the cylinder being small, or on the order of a machine fit, to prevent the passage of water between the members. Although other materials may be used the plunger is preferably made of brass in order to reduce the friction between it and the casing and in order that any wear between the two will be absorbed primarily by the plunger.

The plunger has a central portion or waist 18 of slightly smaller diameter than the upper and lower end portions 19 and 20, which is adapted to receive a pocket or slug of liquid in order to improve the seal between the outside of the plunger and the wall of the casing. The upper end 19 of the plunger is provided with means for engaging a rod or the like and comprises a tapped recess 21 adapted to receive the threaded end 22 of a plunger or pump rod 23.

The plunger has an off center longitudinal bore 24 providing communication between the ends of the plunger and a one-way ball check valve 25, which includes a retaining spring member 26 or the like, and is positioned near the upper extremity of the plunger.

Positioned above the plunger 17 is a valve seat member 30 which is substantially cylindrical and is wedged or otherwise tightly received in the upper portion of the well cylinder to provide a fluid tight joint. The valve seat member has a central bore 31 for the plunger rod 23 which is adapted to reciprocate in the bore of the valve seat member. The bore 31 is substantially cylindrical but includes spaced grooves 32 which extend the length of the bore and provide ports or communicating channels around the plunger rod longitudinally of the bore.

The upper end portion of the valve seat member has a tapered or conical depression 33 providing a valve seat. A plurality of radially spaced

55

bore 34 in the valve seat member extend longitudinally through the valve from its lower end to adjacent the valve seat 33 at which they are curved or directed at substantially right angles to the valve seat. These bores provide communication for the fluid within the cylinder below the valve seat member to the valve seat.

A valve member 35 is provided for the valve seat and has a lower conical end 36 which is adapted to be snugly received by the valve seat 33. The valve member is also provided with a bore 37 which is of a dimension to position the valve member and permit it to slide on the plunger rod. The upper end 38 of the valve member is preferably of a tapered configuration similar to that of the lower end in order that the other end of the valve may be used when the first becomes unreasonably worn. Because of the tapered configuration of the valve member and the valve seat, the fit between the two will tend to remain tight even though reasonable wear takes place.

In the operation of the device the cylinder is attached to the well housing or to other well sections so that the inlet ports 16 are below the normal level of the water in the well. The plunger rod 23 whose lower end is engaged with the plunger 17 is reciprocated by suitable means such as a motor, hand pump linkage, or the like. With the plunger in its lowermost position in which the face of the lower end 20 is prevented from dropping out of the casing by the flanges 13 of the cap 12, water may enter the space between the plunger and the valve seat member 30.

As the plunger rod is raised, thus moving the plunger upwardly, the check valve 25 in the plunger closes or remains closed thus preventing the downward flow of water through the bore 24; the water in the space between the plunger and the valve seat member is forced upwardly through the bores 34 and the channels 32 in the valve seat member and moves the valve member 35 upwardly and off the seat 33, permitting the water to be raised in the well pipe coupling 15 above the valve. After the plunger 17 has reached the extreme of its upward movement it reverses direction and begins to move downwardly. The water beneath the plunger then tends to move upwardly through its bore 24 and lifts the check valve 25 off its seat to permit the water to enter the space between the valve seat member and the plunger. Similarly, when the plunger stops its upward movement and starts downwardly the pressure holding the valve member 35 off its seat is released causing the valve to close and prevent flow of water downwardly therethrough. When the plunger reaches its lowest extreme of movement the space between it and the valve seat member is filled with water ready to be raised on the next upward stroke of the plunger.

It will be apparent that the present invention includes a well cylinder pump construction having a closely fitting reciprocable valve plunger member adapted to alternately force water upwardly through a valve member, and in which no flexible parts such as leather or rubber cup members are provided which may pick up foreign matter and reduce the efficiency of the device.

It will be obvious to those skilled in the art that various changes may be made in the invention without departing from the spirit and scope thereof and therefore the invention is not limited by that which is shown in the drawings and described in the specification but only as indicated in the appended claims.

What is claimed is:

1. A well cylinder comprising a well casing having a plurality of circumferentially spaced apertures adapted to be positioned below the water level in a well; a plunger snugly received by the casing and adapted to reciprocate therein, the plunger having a portion of smaller diameter near its central portion and adapted to receive fluid to seal the plunger from the passage of fluid longitudinally thereof between it and the casing, the plunger having an off center bore extending between its ends and a one-way valve positioned in the upper portion of the bore and adapted to permit fluid to flow upwardly through the plunger only; a plunger rod engaged with the plunger and extending upwardly in the well casing; a valve seat member fixed in the casing above the plunger and having a central bore to slidably receive the plunger rod, the bore having a plurality of longitudinal grooves providing communication around the plunger rod longitudinally of the bore from beneath the valve seat member to its upper portion, the upper portion of the valve seat member having a conical depression forming a valve seat, and a plurality of radially spaced bores extending longitudinally through the valve seat member providing communicating channels from beneath the valve seat member to the valve seat; and a valve member having a conical end adapted to be received on the valve seat and to cover the ends of the grooves of the valve seat member bore and the ends of the radially spaced bores communicating with the valve seat, the valve member having an axial bore for receiving the plunger rod, whereby liquid may be received in the casing through its circumferentially spaced apertures in the space between the plunger and the valve seat member and raised by means of the plunger through the valve seat member, the valve member being raised off its seat by the pressure of the water through the bores and grooves of the valve seat member, and whereby lowering of the plunger permits the valve member to seat and prevent the passage of water downwardly through the valve seat member and whereby the valve in the upper portion of the plunger on its downward movement permits water to pass upwardly through the plunger and into the space between it and the valve seat member.
2. A well cylinder comprising a well casing having a plurality of circumferentially spaced apertures adapted to be positioned below the water level in a well; a plunger snugly received by the casing and adapted to reciprocate therein, the plunger having a bore extending between its ends and a valve positioned in the upper portion of the bore and adapted to permit fluid to flow upwardly through the plunger only; a plunger rod engaged with the plunger and extending upwardly in the well casing; a valve seat member fixed in the casing above the plunger and having a central bore to slidably receive the plunger rod, the bore having a plurality of longitudinal grooves providing communication around the plunger rod longitudinally of the bore from beneath the valve seat member to its upper portion, the upper portion of the valve seat member having a tapered depression forming a valve seat, and a plurality of radially spaced bores extending longitudinally through the valve seat member providing communicating channels from beneath the valve seat member to the valve seat; and a valve member having a tapered end adapted to be received on the valve seat and to cover the ends of the grooves of the valve seat member bore and the ends of the

the radially spaced bores communicating with the valve seat, the valve member having an axial bore for receiving the plunger rod, whereby liquid may be received in the casing through its circumferentially spaced apertures in the space between the plunger and the valve seat member and raised by means of the plunger through the valve seat member, the valve member being raised off its seat by the pressure of the water through the bores and grooves of the valve seat member, and whereby lowering of the plunger permits the valve member to seat and prevent the passage of water downwardly through the valve seat member and whereby the valve in the upper portion of the plunger on its downward movement permits water to pass upwardly through the plunger and into the space between it and the valve seat member.

3. A well cylinder comprising a well casing having a plurality of circumferentially spaced apertures adapted to be positioned below the water level in a well; a plunger snugly received by the casing and adapted to reciprocate therein, the plunger having a bore extending between its ends and a valve positioned in the upper portion of the bore and adapted to permit fluid to flow upwardly through the plunger only; a plunger rod engaged with the plunger and extending upwardly in the well casing; a valve seat member fixed in the casing above the plunger and having a central bore to slidably receive the plunger rod, the upper portion of the valve seat member having a tapered depression forming a valve seat, and a plurality of radially spaced bores extending longitudinally through the valve seat member providing communicating channels from beneath the valve seat member to the valve seat; and a valve member having a tapered end adapted to be received on the valve seat and to cover the ends of the radially spaced bores communicating with the valve seat, the valve member having an axial bore for receiving the plunger rod, whereby liquid may be received in the casing through its circumferentially spaced apertures in the space between the plunger and the valve seat member and raised by means of the plunger through the valve seat member, the valve member being raised off its seat by the pressure of the water through the bores of the valve seat member, and whereby lowering of the plunger permits the valve member to seat and prevent the passage of water downwardly through the valve seat member and whereby the valve in the upper portion of the plunger on its downward movement permits water to pass upwardly through the plunger and into the space between it and the valve seat member.

4. A well cylinder comprising a well casing having a plurality of circumferentially spaced apertures adapted to be positioned below the water level in a well; a plunger snugly received by the casing and adapted to reciprocate therein, the plunger having a bore extending between its ends and a valve positioned in the upper portion of the bore and adapted to permit fluid to

flow upwardly through the plunger only; a plunger rod engaged with the plunger and extending upwardly in the well casing; a valve seat member fixed in the casing above the plunger and having a central bore to slidably receive the plunger rod, the upper portion of the valve seat member having a tapered depression forming a valve seat, and a plurality of bores extending through the valve seat member providing communicating channels from beneath the valve seat member to the valve seat; and a valve member having a tapered end adapted to be received on the valve seat and to cover the ends of the radially spaced bores communicating with the valve seat, the valve member having an axial bore for receiving the plunger rod, whereby liquid may be received in the casing through its circumferentially spaced apertures in the space between the plunger and the valve seat member and raised by means of the plunger through the valve seat member, the valve member being raised off its seat by the pressure of the water through the bores of the valve seat member, and whereby lowering of the plunger permits the valve member to seat and prevent the passage of water downwardly through the valve seat member and whereby the valve in the upper portion of the plunger on its downward movement permits water to pass upwardly through the plunger and into the space between it and the valve seat member.

5. A well cylinder comprising a well casing having one or more apertures adapted to be positioned below the water level in a well; a plunger snugly received by the casing and adapted to reciprocate therein, the plunger having a valved bore permitting flow upwardly through the plunger only; a pump rod attached to the plunger for reciprocating the rod and plunger; a valve seat member in the casing above the plunger and having a first bore to slidably receive the plunger rod, the valve seat member having a valve seat at its upper end, and a plurality of second bores providing communicating channels from beneath the valve seat member to the valve seat; and a single valve member for the valve seat and adapted to cover all of the second bores extending to the valve seat when seated, the valve member having a bore for slidably receiving the pump rod.
